3 Claims. (Cl. 137—8)

This invention relates to a method and apparatus for effecting precision blending of a composite fluid medium for flow through a conduit system. In particular, there is contemplated a method and apparatus which is adapted to proportion sand and oil for use in the hydraulic fracturing of earth formations.

In treating an oil well producing formation to increase its productivity, it is a common practice to introduce a fracturing fluid into the well and to subject the fluid to high pressure to cause a fracturing and consequent permeability increase in the formation. A particularly efficient fluid medium for this purpose comprises a refined or crude oil in which is interspersed sand which functions as a means to prop or hold open formation fractures formed during the well treating operation.

In performing sand-oil fracturing treatments, the sand-oil mixture is conventionally prepared at the well site. At the site, it may be necessary to blend the sand and oil in such quantity as to enable well injection rates on the order of 40 to 50 barrels per minute of treating medium. With such large volume demands, substantial problems are presented in controlling the blending of the sand and oil components so as to consistently and accurately maintain what has been found to be the optimum sand to oil ratio.

In controlling the proportions of medium components, density measuring means may be employed to obtain density measurements of the blended medium which are reflective of the component ratios. In obtaining such measurements, however, because of operational conditions, it may become necessary to dispose the gravity measuring apparatus at a position remote from the site of medium component blending. This arrangement is advantageous in that the gravity determining apparatus, thus positioned, effects a measurement of the medium under stabilized flow conditions and at a point in relatively close proximity to the site of medium use. However, because of the remoteness of the gravity measurement from the blending site, there is introduced an undesirable time lag between the time of blending and the time of gravity determination and subsequent proportion correction.

In addition to the problems involving the placement and timely utilization of the gravity measuring apparatus, there is also involved a substantial abrasion problem in the preparation of the sand-oil mixture. In blending the oil and sand, considerable agitation is required. However, where mechanical agitators are employed, they are prone to undergo severe wear as a result of sand induced abrasion.

Recognizing the need for an improved method and apparatus for blending oil and sand constituents, it is an object of this invention to provide a method and apparatus for effecting precision blending of a composite fluid medium having liquid and particulate solid components.

It is a further object of this invention to provide such an apparatus and method in which the medium component proportions are rapidly corrected when deviations from predetermined proportions occur.

It is an additional object of this invention to provide such a method and apparatus in which the blending of medium components is facilitated by the agitating action

2

of the blended medium itself so as to obviate mechanical wear problems.

To accomplish the foregoing objectives, there is contemplated a method of blending a composite fluid medium for flow through a conduit system wherein a liquid and a relatively heavy, particulate solid component are separately conveyed into the system and there blended to form the medium. Subsequent to this blending, the flow of the medium is accelerated to a rate exceeding the combined rate of component flow into the system. A portion of the accelerated medium flow is diverted and returned to the blending zone to agitate the medium components during the blending. The density of the accelerated medium flow is measured; and, in response to this measurement, the flow of the solid component into the system is regulated so as to maintain a consistent medium density. The flow of the liquid component entering the system, which is determinative of the solid component inflow, is regulated to maintain the combined component inflow entering the system equal to the medium outflow.

The apparatus for accomplishing the aforesigned blending includes a blending receptacle for receiving medium components, first conduit means for supplying the liquid component to the receptacle and second conduit means for supplying the solid component to the receptacle. Third conduit means are employed for conveying the blended medium from the receptacle. Rotary pump means are utilized in the third conduit means to accelerate the medium flow to a rate exceeding the combined component flow rate into the system. First branch conduit means extend from the third conduit means to return a proportion of the accelerated medium flow to the receptacle to effect agitation of the medium components. Second branch conduit means also extend from the third conduit means to return another proportion of the accelerated medium flow to the receptacle. In this second branch conduit means there are included means for measuring the density of the flowing medium. Control means are provided which are responsive to the density measurement of the medium flow through the second branch conduit means for regulating the flow of the solid component into the system whereby a consistent medium density is maintained. Means are also provided for measuring the medium level in the receptacle as well as control means which are responsive to the medium level measurement. Such control means regulate the inflow of the liquid component into the system whereby the combined liquid and solid inflow rate is maintained equal to the medium outflow rate from the system.

In describing the operational details of the method and apparatus with which this invention is concerned, reference will be made to the accompanying drawing setting forth a schematic representation of the conduit system.

In the self-contained blending system illustrated in the drawing, there is included a liquid material reservoir 1 for storing the oil component of the fracturing fluid and a solid material reservoir 2 for storing the sand component. A mixing tank or receptacle 3 is provided to receive the liquid and solid components from the liquid reservoir 1 and solid reservoir 2.

For conveying the liquid component from the reservoir 1 to the mixing tank 3, conduit means 4 is employed including conduit sections 4a and 4b. For the purpose of transferring the solid component from the reservoir 2 to the mixing tank 3, conduit means 5 is utilized which may be arranged to allow gravity induced flow of the sand. Conduit means 6, extending between the mixing tank 3 and a well head 7 of a well to be treated, is also provided, which means includes sections 6a, 6b, 6c and 6d.

A rotary transfer pump 8, preferably of the centrifugal type, is installed in conduit means 4 between sections 4a

and 4b for conveying liquid to tank 3. The pump 8 may be rated at a capacity of 45 barrels per minute, for example. A booster pump 9 is installed in the intermediate portion of conduit means 6, between sections 6a and 6b for accelerating the outflow of blended medium from the mixing tank. Pump 9, also preferably of the centrifugal type, may be rated at a capacity of 70 barrels per minute, for example. As illustrated, both rotary transfer pump 8 and rotary booster pump 9 may be driven by a common engine 10. Due to their rotary, centrifugal character they may be operated even during periods of flow cessation in the system. Adjacent the well head 7, a high pressure injection pump 11 is installed for forcing the treating fluid carried by conduit means 6 into the well bore.

A branch conduit means 12 extends from conduit section 6b upstream of rotary pump 9 back to the mixing tank 3. Where, for example, conduit section 6b on the discharge side of pump 9 is approximately six inches in diameter, it is contemplated that the by-pass line 12 would be approximately four inches in diameter.

For controlling the density of the blended, treating fluid, a control system is employed including a density meter 13, a controller 14, a valve positioner 15, and a sand valve 16 positioned in conduit means 5 intermediate reservoir 2 and mixing tank 3.

Density meter 13 is installed in a second branch conduit means 17, normally two inches in diameter, which also extends between conduit section 6b and the mixing tank 3. While a variety of conventional meters may be employed, it is preferred that a density meter be utilized such as that shown in the Composite Catalog of Oil Field Equipment and Services, 1960-61 edition, page 2360. This density meter is of the type which generates a pneumatic signal proportional to the density of the fluid medium passing through the conduit in which it is installed. This pneumatic signal is transmitted to the air supplied controller 14 which in turn transmits an operating signal to the valve positioner 15. The position of valve 16, as determined by positioner 15, regulates the rate of sand flow through the conduit 5 required to maintain the desired medium density.

Pneumatically operated controller 14 and valve positioner 15, both being conventional structures in the control art are not illustrated. However, as the inflow of solid material through conduit 5 to maintain a proper density level is dependent upon the outflow load condition, it is preferred that the controller 14 be of the proportional and reset type, the operating characteristics of which are described in the article "Basic Controller Fundamentals" appearing at page 54 in the September 1960, issue of Automation Magazine.

The regulation of the combined inflow of liquid and solid components of the medium is effected by a control system including a pressure or liquid level measuring cell 18 positioned in the mixing tank 3, air supplied controller 19, a valve positioner 20, and an oil valve 21 positioned in conduit section 4b between the rotary pump 8 and the mixing tank 3. The cell 18, controller 19, and valve positioner 20, being conventional and well known apparatus are shown only in schematic form. The cell 18 is designed to issue a pneumatic signal proportional to the deviation of the medium level within the mixing tank 3 from a predetermined point. This signal, when transferred to the controller 19, is converted into an operating signal which, through means of the valve positioner 20, determines the position of valve 21 necessary to cause the oil inflow rate necessary to maintain the predetermined level within the tank 3. As the level condition to be controlled is not variable, the controller may be of the proportional type disclosed in the article "Basic Controller Fundamentals" appearing at page 54 in the September 1960, issue of Automation Magazine.

In addition to the automatic flow controlling valves in the system, manual valves such as valves 22, 23, and 24 are provided. Valve 22, positioned between conduit sec-

tions 6b and 6c, allows the medium supply to be disconnected from the well head as, for example, during initial blending operations or at the conclusion of a phase of an injection operation. By means of the manual valve 23, the by-pass flow through branch conduit 12 may be reduced where necessary to accommodate peak load demands at the well head. Manual valve 24 enables the liquid supply to be interrupted in the case of an emergency.

With the apparatus in operation, the combined liquid and solid component flow rate into the conduit system is regulated to equal the medium outflow rate, i.e. the rate at which medium is injected into a well. The rate of solid material inflow being a function of the blended medium density, this inflow is proportional to and determined by the flow of liquid material entering the system. By controlling the liquid inflow to maintain a constant level of components in mixing tank 3, it is insured that the combined rate of liquid and solid inflow is equal to the outflow of blended medium.

In controlling the system, it is important to insure the availability of at least a minimum supply of the medium components. For purposes of system stability, the available supply rates should be consistent. Accordingly, in meeting the high liquid demand, the use of transfer pump 8 in supplying this component in a positive fashion is of material consequence. While a satisfactory solid component feed arrangement may be obtained by allowing sand to flow by gravity through conduit 5 into mixing tank 3, there may be alternatively employed a more positive jet feed arrangement. In this scheme, sand issuing from reservoir 2 and passed through valve 16 would flow into a hopper and there into the path of a fluid jet. This jet would impel the sand axially through conduit means into the mixing tank 3. By supplying oil as the jet fluid, there may be obtained a premixing of the sand and oil components prior to their entry into the mixing tank 3. The sand feeding jet may be supplied from transfer pump 8 or alternatively by the booster pump 9.

By virtue of the use of the blended medium accelerating, booster pump 9, a particularly efficient density control and blending action is achieved in the system. The use of the by-pass conduits 12 and 17 enables the constant circulation of a material quantity of blended medium through a closed circuit comprising conduit portions 6a, pump 9, conduit portion 6b, parallel branch conduits 12 and 17, and mixing tank 3. This closed circuit within the system enables the rotary pump 9 to be operated constantly and independent of system outflow at a relatively high rate to effect an acceleration of the flow of the blended medium to a rate which is materially greater than the combined liquid and solid component flow rate entering the system. The accelerated flow in this circuit facilitates the obtaining of uniform and complete suspension of the particulate, i.e., sand, component. In thus insuring the forming of a homogeneous suspension or slurry, the accuracy of the density meter signal as measured in the circuit is enhanced. In addition, and of considerable importance, the time lag is greatly reduced between the time of medium blending and the time of obtaining a measure of medium density at a point of stabilized flow, such that timely corrections of density deviations may be effected.

An additional advantage in accelerating the medium flow involves the obtaining of the relatively high speed flow in relatively high capacity branch conduit 12. This rapid and material flow, when returned to the mixing tank, in and of itself, is sufficient to produce an agitating or blending action of the components entering the tank such that mechanical blending devices are not required.

While the method and apparatus of this invention have been described in connection with their utilization in the blending of a sand and oil slurry for use in well fracturing operations, it is readily apparent that their applicability is not limited with respect to the components of a

slurry being blended nor with respect to the intended function of the blended slurry. Clearly, for example, the liquid components might be water, gelled water, a light hydrocarbon, etc. Similarly, solid components other than sand might be utilized, of which components cement is only one example. Departures from the preferred and described embodiment of the invention will readily occur to those skilled in the art which are well within the scope of the invention as defined in the appended claims.

We claim:

1. A method of effecting precision blending of a composite fluid medium for flow through a conduit system, said method comprising: conveying a liquid component of said medium into said system, conveying a relatively heavy, particulate, solid component of said medium into said system, blending said liquid and solid components to form said composite medium, applying pump pressure to said thus-formed medium so as to accelerate its flow to a rate exceeding the combined liquid and solid component flow rate into the system, diverting a first portion of said accelerated medium flow and using said first portion to agitate said liquid and solid components during said blending, with the rate of flow of said first portion being selectively variable, diverting a separate, second portion of said accelerated medium flow, independent of said first portion, and mixing said second portion with said solid and liquid components during blending, measuring the density of the medium flow in said second diverted portion after the acceleration thereof, and at a point within said system where said medium flow is continuously subject to pump pressure and in continuous motion, regulating the flow of said solid component entering said system in response to the thus measured density of said medium to maintain a consistent medium density, and regulating the flow of said liquid component entering said system to maintain the combined liquid and solid component inflow rate equal to the medium outflow rate from the system.

2. An apparatus for effecting precision blending of a composite fluid medium for flow through a conduit system, said apparatus comprising: a blending receptacle for receiving medium components, first conduit means for supplying a liquid component of said medium to said receptacle, second conduit means for supplying a relatively heavy, particulate solid component of said medium to said receptacle, third conduit means for conveying said blended medium from said receptacle, first rotary pump means for conveying said liquid component through said first conduit means, second rotary pump means for accelerating the medium flow in said third conduit means to a rate exceeding the combined liquid and solid component flow rate into the system, first branch conduit means extending from said third conduit means to return a portion of said accelerated medium flow to said receptacle to agitate said liquid and solid components during said blending, second branch conduit means extending from said third conduit means to return a portion of said accelerated medium flow to said receptacle, means for measuring the density of medium flowing through said second branch conduit means, first valve means in said second conduit means for regulating the inflow of said solid component, control means responsive to the density measurement of said medium flow through said second branch conduit means for regulating the position of said first valve means to thereby regulate the inflow of said solid component through said second conduit means whereby a consistent medium density is maintained, means for measuring the medium level in said receptacle, second valve means in said first conduit means for regulating the inflow of said liquid component, control means responsive to the medium level measurement in said receptacle

for regulating the position of said second valve means whereby the combined liquid and solid component inflow rate is maintained equal to said medium outflow rate from the system, and valve means in said first branch conduit means for selectively varying the flow therethrough, said third conduit means and second branch conduit means being continuously subject to pump pressure applied by said second rotary pump means whereby the flow of said medium through said second branch conduit means is continuously subject to pump pressure and is in continuous motion, with said flow through said second branch conduit means being independent of the flow through said first branch conduit means.

3. An apparatus for effecting precision blending of a composite fluid medium for flow through a conduit system, said apparatus comprising: a blending receptacle for receiving medium components, first conduit means for supplying a liquid component of said medium to said receptacle, second conduit means for supplying a relatively heavy, particulate solid component of said medium to said receptacle, third conduit means for conveying said blended medium from said receptacle, first rotary pump means for conveying said liquid component through said first conduit means, second rotary pump means for accelerating the medium flow in said third conduit means to a rate exceeding the combined liquid and solid component flow rate into the system, first branch conduit means extending from said third conduit means to return a portion of said accelerated medium flow to said receptacle to agitate said liquid and solid components during said blending, second branch conduit means extending from said third conduit means to return a portion of said accelerated medium flow to said receptacle, means for measuring the density of medium flowing through said second branch conduit means, control means responsive to the density measurement of said medium flow through said second branch conduit means for regulating the inflow of said solid component through said second conduit means whereby a consistent medium density is maintained, means for measuring the medium level in said receptacle, control means responsive to the medium level measurement in said receptacle for regulating the inflow of said liquid component through said first conduit means whereby the combined liquid and solid component inflow rate is maintained equal to said medium outflow rate from the system, and valve means in said first branch conduit means for selectively varying the flow therethrough, said third conduit means and second branch conduit means being continuously subject to pump pressure applied by said second rotary pump means whereby the flow of said medium through said second branch conduit means is continuously subject to pump pressure and is in continuous motion, with said flow through said second branch conduit means being independent of the flow through said first branch conduit means.
